UNITED STATES PATENT OFFICE.

WILLIAM FONDILLER, OF NEW YORK, N. Y., ASSIGNOR TO WESTERN ELECTRIC COMPANY, INCORPORATED, OF NEW YORK, N. Y., A CORPORATION OF NEW YORK.

PHANTOM LOADING-COIL.

1,231,516.

Specification of Letters Patent. Patented June 26, 1917.

Application filed May 1, 1916. Serial No. 94,695.

To all whom it may concern:

Be it known that I, WILLIAM FONDILLER, a citizen of the United States, residing at New York, in the county of New York and 5 State of New York, have invented certain new and useful Improvements in Phantom Loading-Coils, of which the following is a full, clear, concise, and exact description.

This invention relates to phantom circuit 10 loading in telephony, and in particular to a loading unit by which inductance is added simultaneously to a pair of physical circuits and to a phantom circuit derived from them.

Its object is to secure this simultaneous 15 loading in an efficient manner, to increase the magnetic stability of the loading unit, and to provide for any desired ratio of phantom circuit inductance to physical circuit inductance.

20 These objects are accomplished by providing suitably proportioned gaps of high reluctance in the cores of the coils used for physical circuit loading, and by the use of magnetic bridges of low reluctance arranged 25 to operate in conjunction with the gaps to secure the desired flux distribution due to phantom circuit currents.

The manner in which these objects are accomplished will be further explained in connection with the drawings, in which Figure 30 1 represents a circuit diagram of the two physical circuits and the phantom circuit, including the loading unit; and Fig. 2 is a perspective view of the magnetic structure 35 of the loading unit.

Referring to Fig. 1, 1 and 2 represent two physical circuits which are loaded by including in them inductance coils whose windings are mounted on the semi-toroidal cores 3 and 40 4. 5 is a phantom circuit derived from these as usual by employing the line conductors of each physical circuit in parallel as one effective conductor of the phantom circuit. In magnetic structure, 6 represents a gap or 45 an equivalent break in the magnetic circuit, formed in this case by introducing a strip of non-magnetic material. This material should also obviously be non-conducting to avoid loss of energy in eddy currents.

50 The two loading coil cores are placed in this invention one above the other, in the manner illustrated in Fig. 2. In this latter figure, 6 represents the strip of separating material described in connection with Fig. 55 1, and 7 yokes of magnetic material, prefer-

ably laminated iron, used to form a magnetic bridge of low reluctance to connect the cores of the inductance coils. These magnetic bridges 7 are shown in section in the first figure and are indicated by the same characters.

The operation of the system is as follows:

When currents flow in opposite directions in the two conductors of the physical circuit 1, for example, a magnetic flux is produced which lies in circular paths around the core 3, as is usual in loading of telephone lines. The windings are so arranged, however, that when currents in the conductors of circuit 1 flow in the same direction, as 70 will be the case in phantom operation, north and south magnetic poles will be produced at 8 and 9, respectively, at a given instant, and at the same time south and north magnetic poles at the points 10 and 11 respectively. As a consequence of this, the lines of phantom circuit flux will lie in the two halves of cores 3 and 4 in parallel and will be completed in the magnetic bridges 7. In the first of these cases, namely, that of physical circuit operation, the resultant flux 75 will be linked with the physical circuits only, and in the second with the phantom circuit only; and consequently, the operation of these circuits will be independent.

It has been found that the method of loading phantom circuits which depends solely upon employing a leakage field, is subject to the objection that it is difficult to secure a sufficiently high phantom circuit inductance 80 for a given physical circuit inductance, and it has also been found that the use of loading coils without gaps renders them liable to magnetization by lightning discharge or other heavy currents. Both of these objections are 85 overcome in this invention by the use of gaps, for these add stability to the magnetic circuit and also provide for increasing the reluctance of the paths traversed by the physical circuit flux to any desired value, without increasing the reluctance of the path 90 traversed by the phantom circuit flux.

The semi-toroids 3 and 4 may be of any suitable magnetic material. In practice, it has been found desirable to make them of 105 finely divided iron, the individual particles of which are coated with a thin insulating film, the core structure being formed under high pressure, in the manner described and claimed in an application for patent Serial 110

- No. 89,409, filed April 6, 1916, by James B. Speed, and assigned to the same assignee on the present application. The laminations for the magnetic bridges 7 may be stamped 5 from sheet metal, or may also be of finely divided iron, molded under high pressure. It will be understood that the term "toroid", as used herein, is intended to refer to a ring of any desired cross-section; and that instead of rings, rectangular or other forms of frames might be employed, and that, for want of some broader expression, the term "toroid" is used to denote all such structures. 10 15 What is claimed is:
1. A loading unit adapted for use with two physical circuits and a derived phantom circuit comprising cores with gaps of high reluctance therein, windings on said cores adapted for inclusion in each of the conductors of said physical circuits, and bridges of low reluctance joining said cores and providing paths of low magnetic reluctance for the flux produced in the operation 20 25 of said phantom circuit.
  2. A loading unit adapted for use with

two physical circuits and a derived phantom circuit comprising cores with gaps of high reluctance therein, windings on said cores adapted for inclusion in each of the conductors of said physical circuits, and two bridges of low reluctance joining said cores, the lengths of said gaps and the magnetic reluctance of said bridges being adjusted to secure a desired ratio of phantom circuit inductance to physical circuit inductance. 30 35

3. A loading unit core structure comprising two toroidal core members, bridges of low reluctance between said members at diametrically opposite points, there being a gap of high reluctance transversely intersecting each of said toroidal members. 40

4. A loading unit core structure comprising two toroidal core members, bridges of low reluctance between said members at diametrically opposite points, there being a gap of high reluctance transversely intersecting each of said toroidal members and longitudinally bisecting said bridges. 45

In witness whereof, I hereunto subscribe my name this 29th day of April A. D., 1915.

WILLIAM FONDILLER.
